US00D923642S

(12) **United States Design Patent** (10) Patent No.: **US D923,642 S**
(45) Date of Patent: **** Jun. 29, 2021**

- (54) **DISPLAY SCREEN OR PORTION THEREOF WITH ANIMATED GRAPHICAL USER INTERFACE**
- (71) Applicant: **Apple Inc.**, Cupertino, CA (US)
- (72) Inventors: **Alan C. Dye**, San Francisco, CA (US); **Aurelio Guzmán**, San Jose, CA (US)
- (73) Assignee: **Apple Inc.**, Cupertino, CA (US)
- (**) Term: **15 Years**
- (21) Appl. No.: **29/731,730**
- (22) Filed: **Apr. 17, 2020**

Related U.S. Application Data

- (63) Continuation of application No. 29/662,565, filed on Sep. 6, 2018, now Pat. No. Des. 882,615.
- (51) **LOC (13) Cl. 14-04**
- (52) **U.S. Cl. USPC D14/485**
- (58) **Field of Classification Search**

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a front view of a display screen or portion thereof with animated graphical user interface showing a first image of another embodiment of the claimed design;

FIG. 9 is a second image thereof;

FIG. 10 is a third image thereof;

FIG. 11 is a fourth image thereof;

FIG. 12 is a fifth image thereof;

FIG. 13 is a sixth image thereof; and,

FIG. 14 is a seventh image thereof.

The outer broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-7 and FIGS. 8-14. The process or period in which one image transitions to another forms no part of the claimed design.
